[57] CLAIM

The ornamental design for a picture-hanging bracket, as shown.

DESCRIPTION

FIG. 1 is an isometric view of a bracket embodying my design.

FIG. 2 is an elevation view on a reduced scale of the bracket of FIG. 1.

FIG. 3 is a bottom view of the bracket as shown in FIG. 2.

FIG. 4 is a back view of the bracket as shown in FIG. 2.

FIG. 5 is a top view of the bracket as shown in FIG. 2.

FIG. 6 is a side view of the bracket of FIG. 4.
